MACHINE FOR MANUFACTURE OF WINDOW
ENVELOPES AND LIKE CONTAINERSAlfred Winkler and Max Dünnebier,
Neuwied-on-the-Rhine, GermanyApplication September 18, 1933, Serial No. 689,920
In Germany December 19, 1931

9 Claims. (Cl. 93—61)

This invention relates to a machine for manufacture of envelopes, bags and like containers employing transparent patches or windows of the type, described in our co-pending application filed July 28, 1932, Serial No. 625,398, of which the present invention is a continuation in part, and directed to the apparatus for applying the window patch and sealing gum to the envelope blanks and then simultaneously drying the gum and effecting set of the patch prior to folding thereof.

The principal object of the present invention is to provide a high quality finished product, free from wrinkles and having the patch applied squarely over the window opening.

In accomplishing this and other objects of the invention we have provided improved details of structure, the preferred form of which is illustrated in the accompanying drawings, wherein:

Fig. 1 is a side elevational view of a machine constructed in accordance with our invention, portions of the machine being broken away to shorten the illustration.

Fig. 2 is a longitudinal vertical sectional view through the machine.

Fig. 3 is a plan view of the machine.

Fig. 4 is a diagrammatic view illustrating the steps of operation performed on the blanks as they are moved through the machine.

Referring more in detail to the drawings:

1 and 2 designate right and left side frames of the patch-applying portion of the machine, and supported on the upper edges thereof are roller bed plates 3 and 4. Mounted on the right hand end of the side frames (Fig. 2) at a point below the bed plates is a bracket 5 carrying an upwardly inclined stack-supporting plate 6 on which a stack of envelope blanks 7 is supported for delivery into the machine. The stack of blanks is retained in position on the plate by spaced posts 8 and 9 so that the upper ends of the blanks project a sufficient distance above the rear edge of the plate to permit the lowermost blank in the stack to be engaged by a vacuum nozzle 10 to effect successive withdrawal of blanks from the stack for feed into the machine, as later described.

The blanks may be of various shapes and sizes but for illustrating the operation of the present invention the blanks comprise substantially rectangular sheets wherein the corners *a* and *b* constitute the side flaps and the corners *c* and *d* the bottom and closure flaps of an envelope, which in the present invention the body portions of the blanks are provided with window

openings *e*. The blanks are arranged on the supporting plate so that the flaps *c* are in position to be engaged by the vacuum nozzle and forwarded into the machine.

The vacuum nozzle 10 is carried at the end of an arm 11 that is mounted on a rock shaft 12 extending between upward projections 13 of the bed plates and which is actuated by a cam 14 through a lever 15 connected to an arm 16 on the rock shaft so that upon each rotation of the cam the nozzle is swung toward the stack to engage the bottom blank thereof and then away from the stack to carry the engaged blank into the reach of the first of a series of upper and lower forwarding rollers located along the upper edges of the bed plates.

The lower forwarding rollers are designated 17 to 21 inclusive and 28 to 34 inclusive and are mounted on horizontal shafts rotatably supported in suitable bearings in the bed plates at an elevation so that the peripheries of the respective rollers will lie in a horizontal plane to constitute a rolling support for the blanks as they are moved through the machine.

The shafts of the rollers 17, 18, and 19 carry gears 35, 36 and 37 respectively which are inter-connected by idler gears 38 and 39 so that they rotate together in an anti-clockwise direction, Fig. 2.

Cooperating with the roller 17 and located at opposite sides of the nozzle 10 are spaced gripping rollers 40 and 41 that engage the sides of the flap *c* as it is bent downwardly upon retractive movement of the nozzle in withdrawing the engaged blank from the stack.

The rollers 40 and 41 are mounted on a shaft rotatably supported in the projecting portion 13 of the side frame and are driven by a gear 42 meshing with the gear 35 on the lower roller 17.

Cooperating with the roller 18 are spaced rollers 43 and 44 to feed the blanks onto a straightening and aligning belt 45 wherein the blanks are overlapped in shingle formation, as illustrated in Fig. 3. The belt 45 operates over the rollers 19 and 20 and over a horizontal plate 46 supported therebetween, as best illustrated in Fig. 2. The belt is tensioned over the table by a suitable tensioning device indicated at 47.

In order to retain the blanks in overlapped formation on the belt we provide spaced sets of guide rollers 48, 49, 50, and 51 which are preferably yieldingly tensioned against the belt by suitable tensioning means not shown.

In order that the forwarding rollers 17 and 18 including the belt 45 may be operated intermit-

tently between movements of the vacuum nozzle, the shaft for the roller 17 is intermittently actuated by means of a Geneva gearing 52. The Geneva gearing includes a Maltese cross member 53 mounted on a stub shaft 54 extending from the frame 1 and which carries a sprocket 55 for driving a sprocket 56 on the shaft of the roller 17 through a chain 57 operating over the respective sprockets. The Maltese cross member 10 is intermittently actuated by the Geneva block 58 that is fixed on a horizontal shaft 59 having its ends rotatably mounted in the side frames 1 and 2 and which is actuated by a chain 60 operating over a sprocket 61 thereon and over a 15 sprocket 62 on a counter shaft 63 extending between the side frames at a point below the shaft 59. The shaft 63 is operated from a longitudinally extending drive shaft 64 through beveled gears 65 and 66 on the respective shafts, Fig. 3.

20 The roller 21 at the delivery end of the belt 45 cooperates with spaced driving wheels 67 which are mounted on a shaft 68 extending above the roller 21 and which is operated continuously at a desired speed by a sprocket 69 driven from a 25 sprocket 70 by means of a chain 71. The sprocket 70 is mounted on a counter shaft 72 rotatably mounted in the side frames 1 and 2 at a point in advance of the counter shaft 59 and is driven therefrom through a longitudinally extending 30 shaft 73. The shaft 72 extends along the upper edge of the side frame 1 and is rotatably mounted in bearings 74 and 75 carried by brackets 76 projecting from the side frame, as best illustrated in Figs. 1 and 3. The shaft 73 is actuated 35 by a bevel gear 77 meshing with a bevel gear 78 fixed to the end of the counter shaft 59. The counter shaft 72 is operably connected with the shaft 73 by intermeshing bevel gears 79 and 80 fixed to the respective shafts, as illustrated in 40 Figs. 1 and 3.

As soon as the blanks are engaged by the continuously running rollers 21 and 67, they are individually separated from the blanks being advanced by the belt 45 for separated travel 45 through the patch applying portion of the machine.

In order to time the blanks for proper admission to the patch-applying mechanism we provide a shaft 81 extending across the bed plates 50 between the rollers 21 and 22 for mounting spaced stop members 82 having upwardly extending fingers 83 adapted to swing across the path of travel of the blanks to momentarily intercept their movement until they are in correct timed relation with the patch-applying mechanism so that the patch is applied in the proper location over the window openings in the blanks.

The stop members 82 having depending arms 84 carrying rollers 85 contacting with cams 86 are 60 carried on a shaft 87 that extends between the bed plates. The cam shaft 87 is driven by a gear 88 meshing with a gear 89 on the counter shaft 72 through a train of idle gears 90, as best illustrated in Fig. 1. The stop members thus described are preferably arranged to engage the blanks at opposite sides of the flap c so that the point thereof is in position to be engaged by the roller 28 which is the first roller for aiding the advancement of the blank through the patch- 65 applying mechanism.

Cooperating with the roller 28 and mounted on a shaft 128 carried by upward extensions 129 of the bed plates is a segmental roller 130 including an arcuate portion 131 extending substantially half the diameter thereof. The posi-

tion of the arcuate portion of the roller is so timed relatively to the continued advance of the blanks that the point of the blank lies free upon the roller 28 until engaged by the forward edge thereof, at which time the stop fingers are moved 5 out of engagement with the blank to allow its feed between the segmental roller and the roller 28. When the arcuate portion of the segmental roller moves in contact with a blank, it grips the blank and continues its forward travel 10 through the machine.

Cooperating with the rollers 29, 30, 31, 32, and 33 are pressure rollers 142, 143, 144, 145, and 146 respectively for guiding the blank through the portion of the machine for applying adhesive 15 about the edge of the window openings to receive the transparent patch, as later described. Supported above the pressure rollers 142 and 144 by upward extensions of the bed plate is an adhesive-containing pan 147 having rotatably 20 mounted therein an adhesive pick-up roller 148 for depositing adhesive on a transfer roller 149 rotatably supported above the rear edge of the pan in contact with the pick-up roller 148. The adhesive is removed from the transfer roller and 25 applied to the blank as it emerges from under the pan by an applicator 150 carried on the end of a rotating arm. The arm is mounted on a shaft 151 spaced above the pressure rollers 145 and is carried in the extensions of the bed plates 30 supporting the adhesive pan.

The rollers 28 to 33 inclusive and the segmental roller 130 together with the adhesive applicator shaft 151 are driven from a counter shaft 152 mounted directly below the rollers 29 and 30. The 35 counter shaft 152 projects entirely through the side frame and carries on its end adjacent the longitudinal shaft 73 a beveled gear 153 meshing with a beveled gear 154 on the shaft 73. The opposite end of the counter shaft 152 carries a 40 gear 155 that meshes with gears 156 and 157 on the shafts of the rollers 29 and 30 respectively through an idle gear 158. The opposite ends of the last named shafts are provided with gears 159 and 160 respectively to drive the remaining 45 rollers 130, 131, 132, and 133.

The roller 28 is driven from the gear 159 through an idle gear 161 meshing with a gear 162 on the shaft of the roller 28 and the segmental roller 130 is provided with a gear 163 which 50 meshes with a gear 162. The shafts of the rollers 31, 32 and 33 are provided with gears 164, 165, and 166 and are interconnected by idle gears 167, 168, and 169. The gear 167 meshing with the gear 160 on the shaft of the roller 30 transmits motion to the other gears of the train. The adhesive applicator shaft 151 is provided with a gear 170 meshing with the gear 165 and the shaft of the transfer roller 149 is driven by a gear 171 meshing with the gear 170. The opposite end 60 of the transfer roller shaft carries a gear 172 meshing with a gear 173 to drive the adhesive pick-up roller 148. The forwarding rollers as well as the segmental roller 130 and the adhesive applicator shaft are thus operated in timed 65 relation with each other.

After adhesive has been applied to the blank, the blank continues its travel aided by the rollers 33 and 146 to a point where a transparent window strip or patch is applied, as now to be described.

Rotatably supported on extensions 174 mounted on the left hand ends of the bed plates (Fig. 2) is a shaft 175 supporting a roll of transparent paper or the like 176 from which the window

patches are formed. The end of the paper strip is threaded between feed rollers 177 and 178 across a downwardly inclined table 179 toward the path of the blanks and between shear blades 180 and 181 respectively mounted above and below the table 179 and operating through a slot 182 therein. The feed roller 177 is intermittently operated and partially rotated in timed relation with the feeder rollers so that the required amount of strip is fed at each rotative operation of the machine.

Fixed on the end of the shaft carrying the roller 177 is a gear 183 that meshes with a gear 184 rotatably mounted on the stub shaft 185 extending from the frame extension 174. Fixed in driving relation with the gear 184 is a smaller gear 186 meshing with a gear 187 rotatably supported on a stub shaft 188 mounted on the frame extension at a point below the shaft 185. Fixed in driving relation with the gear 187 is a ratchet wheel 189 intermittently operated by a pawl 190 carried at the end of an arm 191 swingingly mounted on the shaft 188. The arm carrying the pawl is operated by a pitman 192 having a ring 193 operating over an eccentric 194 carried on the projecting end of a roller shaft 195. The roller shaft 195 is driven from the gear 169, previously described, by means of a gear 196 meshing with an idle gear 197 so that the eccentric is rotated in timed relation with the forwarding rollers. Rotation of the eccentric swingingly reciprocates the arm to intermittently actuate the ratchet wheel between each operation of the machine and to rotate the chain of gears driving the strip feeding roller 177 to feed the proper amount of strip through the shear blades to cover the window opening. The shear blades are then actuated from the shaft 195 by a cam 198 that actuates a crank lever 199 operably connected with the shear blades through a pitman 200 to sever the measured section of the strip.

Rotatably mounted under the lower edge of the shear table 179 and in position to engage the strip is a vacuum roller 201 having a series of openings 202 through which a vacuum is drawn to engage the forward edge of the strip section directly after the cut is made. The roller 201 operates in timed relation with the knives and with the movement of the blank so that the vacuum roller carries the window strip into contact with the blank at the time the window opening is passing over a roller 203 which is carried on the shaft 195, previously described. In order to drive the vacuum roller 201, it is provided with a gear 204 that meshes with the gear 196 on the shaft 195 previously described.

The blanks with the transparent panels applied to the window openings are now brought to a station for gumming the closure flaps *d* of the envelopes in order that the gumming of the closure flaps may be dried and the adhesive affixing the transparent patches may be firmly set at the same time. To gum the closure flaps it is desirable to bunch the blanks in overlapped formation in such a manner that only the portions of the flaps to receive the gum are exposed. To accomplish this we provide a rotary vacuum disk 205 having approximately three times the diameter of the vacuum rollers previously described. The vacuum disk 205 is equipped at equal distances about its circumference with sets of apertures 206 through which a vacuum is drawn to engage the blanks as they are delivered across the roller 34.

The disk 205 is mounted on a countershaft 207 rotatably carried in the side frames, and is driven by a gear wheel 208 that meshes with a gear 209 on the shaft of the roller 203 which in turn is driven from the gear 196 by a gear 210 meshing therewith at the opposite side of the machine. The gears are so timed that the vacuum wheel makes one revolution during one revolution of the forwarding rollers. Therefore, three successive blanks are engaged upon each revolution of the vacuum disk in order that the envelopes may be delivered thereby to the gumming belts in overlapped relation with the required amount of flap exposed for the gumming.

The disk 205 rotates in contact with a fixed disk 211 having a connection 212 with the vacuum pump (not shown) and over which the channels 206 connecting the ports 206 rotate to make them effective for gripping the blanks to carry them through feed rollers 213 and 214 which are driven at substantially the speed of the forward rollers as later described. The rollers 213 and 214 deliver the blanks in overlapped formation between spaced sets of upper and lower endless belts 215-215' and 216-216', respectively. The sets 25 of belts are spaced apart to engage the side flaps of the blanks and operate over a downwardly inclined plate 217 carried between the side frames 1 and 2 at a point below the vacuum disk 205.

The belts 216-216' operate over a roller 218 working through a slot 219 in the table, over the table 217, over a roller 220 carried by the side frames, and over a driving roller 221 operable in timed relation with the rollers for the belts 215-215'. The belts 215-215' operate over a 35 drive roller 222, over a roller 223 supported above the table in parallel relation with the roller 218, over a roller 224, and over an idling roller 225, as best illustrated in Fig. 2.

The driving pulley for the belts 216-216' is 40 provided with a sprocket 226 that is driven by a chain 227 operating over a sprocket 228 carried on a stub shaft 229 projecting from the side frame 1. Supported on the stub shaft in driving relation with the sprocket is a gear 230 meshing with a gear 231 driven by a gear 232 carried on a pulley shaft 233 extending horizontally between the side frames. The shaft 233 is driven from the shaft 207 by a chain 235 running over sprockets 236 and 237 on the respective shafts. 50

The drive roller 222 for the belts 215-215' carries a gear 238 which meshes with a gear train 239 driven by a gear 240 meshing with the gear 241 on the shaft of the drive roller for the belts 216-216', as best illustrated in Fig. 1. The feed 55 roller 213 previously mentioned is driven from the gear 239 by a gear 242 on the roller shaft.

The lower run of the belts 215-215' carried by the roller 224 is preferably yieldingly tensioned against the run of the belts 216-216' operating 60 over the table 217, and we have, therefore, mounted the roller 224 at the ends of arms 243 that are suspendingly supported by the side frames, the arms being connected with the side frames by springs 244. 65

While the overlapped blanks are conveyed between the runs of the belts thus described, the tops of the flaps are exposed to receive the gum which is applied by an applicator 245 (Fig. 2) carried above the inclined plate 217 between the 70 arms 243. When the blanks are delivered from the ends of the belts they are discharged between a second pair of spaced belts 246 and 247 and an intermediate belt 248. These belts operate at slightly greater speed than the speed of the belts 75

previously described in order to effect slight separation of the blanks to prevent the gum on one blank sticking to the gum of an adjacent blank.

The belts 246 and 247 operate over a pulley 249 loosely mounted on the shaft 233, previously mentioned, in such a manner that the peripheries of the belts operate in line with the blanks discharged between the belts 215-216. The belts 246 and 247 extend to the opposite end of the machine (Fig. 2) and operate over a somewhat larger pulley 250 and over a table 251 and guide rollers 252, 253, 254 and 255, the belt being tensioned by a tightening device indicated at 256 (Fig. 2). The lower run of the belts 246 and 247 cooperates with the upper run of the belt 248 to retain the blanks therebetween. The lower belt 248 is, therefore, retained in operative position by guide rollers 257 and 258 carried by the side frames adjacent the pulley 249, over a guide roller 259 positioned below the rollers 255, over a roller 260 carried by the side frames of the folding section of the machine, over a roller 261 carried by the side frames above the pulley 250, over a tensioning roller 262 carried above the table 251, and back over the larger drive pulley 250.

The roller 257 and the pulley 249 are arranged relatively to each other to form a gradually closing throat between the runs of the belts to receive the blanks as they are discharged from the belts 215 and 216.

The belts thus described are driven by the pulley 250 which is actuated by a worm gear 263 that meshes with a worm 264 on an extension 265 of the shaft 64 previously described. The extension 265 and the shaft 64 are coupled through intermeshing bevel gears 266, 267, and 268, as best illustrated in Figs. 1 and 3. The intermediate bevel gear 267 is driven by a power shaft 269 extending between the side frames 1' and 2' of the folding section of the machine.

The lower runs of the belts 246 and 247 and upper run of the belt 248 carrying the blanks therebetween travel through a drying chamber 270 into which warm air is discharged against the glue portions of the blanks to aid in their drying.

After the blanks have been delivered from between the belts at the right hand end of the machine (Fig. 2), they pass onto a belt 272 that is intermittently actuated in the same manner as the belt 45, previously described, to reassemble the blanks in overlapped formation in case some of them have lost their position and spacing in the drying belts.

The belt 272 operates over spaced rollers 273 and 274 and over a table 275 on which operate pressure rollers 276, 277, and 278. The belt is driven from the roller 273 which is provided with a sprocket 279 actuated by a chain 280 from a Geneva gearing 281 that is operated from the countershaft 269 through a chain 282.

From the belt 272 the blanks are delivered through continuously moving rollers 283 and 284 operating at the same peripheral speed as the following rollers to allow spacing thereof for readjustment by stop fingers 285 and 286 similar to the stop fingers previously described. These stop fingers are operated in such a manner that the finger 286 moves into the path of the blanks to momentarily intercept their travel until they are in timed relation with the flap-gluing and folding mechanism later described, whereupon the stop fingers 286 are retracted and the fingers 285 are moved into position to push the blank

between creasing rolls 288 and 289 where the side flaps *a* and *b* and the closure and bottom flaps *d* and *c* are scored preparatory to folding.

The cam shaft operating the stop fingers is actuated from a gear 290 fixed in driving relation with the continuously rotating member of the Geneva gear which meshes with a driving gear 291 on the cam shaft. The feed rollers 283 and 284 are driven by intermeshing gears 292 and 293 that are rotated by an intermediate gear 294 meshing with the gear 291. The scoring rollers 288 and 289 are provided with gears 295 and 296 that are driven from the gear 291 through an idle gear 297.

After the blanks have been scored they are forwarded by rollers 298 and 299 across side flap folders 300 which fold the side flaps on the score lines over on the body portion of the blanks, as best illustrated in Fig. 3. The blank then passes between pressure rolls 301 and 302 operating over the folded edges of the side flaps to press them flat against the body portion of the blank. The blank then continues between pairs of rollers 303 and 304.

Supported above the rollers 303 and 304 is an adhesive pan 305 having an adhesive pick-up roller 306 and an adhesive transfer roller 307 for applying adhesive to an arcuate segment 308. The arcuate segment conforms to the shape of the lower edges of the side flaps and applies adhesive thereto as the blank passes from between the rollers 303 and 304. The applicator segment is carried on a shaft 309 supported by the side frames in position to receive adhesive from the transfer roller. The blank then passes between pressing rollers 310 and 311 which deliver the blanks to flap-bending mechanism later described.

The shafts of the rollers 301 and 302 are provided with intermeshing gears 312 and 313 which are driven from the gear 314 on the shaft of the roller 299 through a gear 315 meshing with the gear 313. The applicator shaft is driven by a gear 316 driven from the gear 313 through a train of gears 317, and the transfer roller is driven from the gear 316 by means of a gear 318.

After the passage of the bottom flap from between the rollers 310 and 311, a swinging finger 319 moves upwardly to raise the flap so that it is in position to be engaged by a finger 320 operable above the path of travel of the blank to fold the bottom flap over the side flaps.

When the envelope emerges from beneath the next pair of rollers 321 and 322 it is directed by a guide plate 323 upwardly, but at this time a tucking finger 324 swings into position to effect bending of the closure flap on its crease line to tuck it under the roller 325 which engages against the roller 322.

The completed envelope is then dropped from the rollers 325 and 322 onto an inclined plate 326 to a stacking mechanism indicated at 327. This mechanism includes a wheel 328 having peripheral lugs 329 for engaging the rear edge of the folded blank and for carrying it into substantially vertical position for stacking, after which the stacks of completed envelopes may be removed and boxed for shipment.

The fingers 320 and 324 are operated by pitmans 332 and 333 actuated by cams 334 and 335 on the shafts of the rollers 311 and 322 respectively. The rollers are rotated by gears 336 and 337 intermeshed with the gear 338 and actuated by an idle gear 339 meshing with the gears 317.

In operating a machine constructed and as- 75

sembled as described, the blanks are placed in a stack on the plate 6 and adjusted in position by the posts 8. The various operating parts of the machine are then adjusted to perform the various operations on the blanks. Upon starting the machine the sucker arm 11 will engage the flap c of the undermost blank in the stack and draw it downwardly within reach of the rollers 40 and 17. The roller 40 will then engage the diverging side edges of the flap to feed the blank onto the straightening and aligning belt 45 in such a manner that the blanks are in overlapped formation, as shown diagrammatically in Fig. 4.

The blanks are then intermittently advanced by the belt to the faster, continuously revolving rollers 68 and 21, which increases the speed of the successive blanks and forwards them into engagement with the stop fingers 83 which are timed to swing into position to momentarily stop each blank until it is in timed relation with the patch-applying mechanism.

The blank will then be forwarded by the segment rollers 130 into and through the gumming mechanism for applying gum about the window opening, as indicated at *j*, Fig. 4.

The rollers 146 and 33 then forward the blank between the vacuum roller 201 and the roller 203, where the transparent strip *k* is applied over the window opening and is pressed into sealing engagement with the adhesive *j*. The vacuum disk 205 then moves into position to assemble the blanks in overlapped formation between the belts 215 and 216, where adhesive is applied to the closure flap *d* indicated at *l*, Fig. 4.

The blanks are then delivered to the drying belts 246, 247, and 248 to be carried back underneath the window-forming mechanism to the folding section of the machine. During their carriage by the belts they pass through the drying chamber 270, where the gum on the closure flap is dried and the patch over the window opening is firmly set.

After the blanks are delivered from the drying belts they are discharged onto the belt 275, where they are reassembled in overlapped formation, as shown in Fig. 4, for individual delivery into and through the flap-folding mechanism.

The blanks, on being discharged from the belt 275, are aligned and properly spaced by the fingers 285 and 286 for travel between the rollers 288 and 289, where they are scored and delivered to the side flap closing members 300 to fold the side flaps over the body portion of the envelope, as shown in Fig. 4.

The blanks are then passed onto the next station where the adhesive is applied by the applicator 308 to the side flaps, as indicated at *m*, Fig. 4. The blank is then advanced to the flap-folding station where the arms 320 and 324 fold the bottom and closure flaps, respectively.

The folded blanks are then dropped down the inclined plate 326 to the stacking mechanism where they are stacked preparatory to boxing.

It is apparent that by effecting set of the adhesive wherewith the patch is affixed prior to the folding operations, the patch is firmly applied and cannot be displaced from its applied position as is the case where the blanks are folded over a wet patch.

What we claim and desire to secure by Letters Patent is:

1. In a machine of the character described, the combination of means for affixing a patch over a window opening in a blank of foldable material including means for applying adhesive

to fix the patch, means for applying gum to a sealing flap of the blank, blank advancing means having direct connection from the patch affixing means and with the means for applying the gum to the sealing flap, means connected in receiving relation with said gum applying means for simultaneously drying the gum and effecting set of adhesive whereby the patch is affixed to the blank, and means for directly delivering the blank from the gum applying means to said drying means.

2. In a machine of the character described, the combination of forwarding means for moving blanks through a fixed path, means cooperating with the forwarding means for affixing patches including means for applying adhesive to fix the patches over the window openings in the blanks, means for applying gum to the sealing flaps of the blanks, blank advancing means having connection with the patch affixing means and with the gum applying means, means for simultaneously drying the gum and effecting set of the adhesive whereby the patches are affixed to the blanks, a conveyor, means for supporting the conveyor in receiving relation to the gum applying means and in direct delivery relation with said drying means for directly delivering the blanks from the gum applying means to said drying means connected with the drying means for folding the blanks.

3. In a machine of the character described, the combination of forwarding means for moving blanks through a fixed path, means located in the path of the blanks for spacing and aligning the blanks on the forwarding means, means cooperating with the forwarding means and operating in timed relation with the spacing means for affixing patches over window openings in the blanks including means for applying adhesive to fix the patches, means for applying gum to the sealing flaps of the blanks, blank advancing means having connection with the patch affixing means and with the gum applying means, means for simultaneously drying the gum and effecting set of the adhesive whereby the patches are affixed to the blanks, a conveyor, and means for supporting the conveyor in receiving relation to the gum applying means and in direct delivery relation with said drying means for directly delivering the blanks from the gum applying means to the drying means.

4. In a machine of the character described, the combination of forwarding means for moving blanks through a fixed path, means located in the path of the blanks for spacing and aligning the blanks on the forwarding means, means cooperating with the forwarding means and operating in timed relation with the spacing means for affixing patches over the window openings in the blanks including means for applying adhesive to fix the patches, means for applying gum to the sealing flaps of the blanks, blank advancing means having connection with the patch affixing means and with the gum applying means including means for lapping the blanks one over the other to expose the sealing flaps of the blanks to the gum applying means, means for simultaneously drying the gum and effecting set of the adhesive whereby the patches are affixed to the blanks, a conveyor, and means supporting the conveyor in receiving relation with the gum applying means and in direct delivery relation with said drying means for directly delivering the blanks from the gum applying means to said drying means.

5. In a machine of the character described, the

- combination of forwarding means for moving blanks through a fixed path, means cooperating with the forwarding means for affixing patches over window openings in the blanks including 5 means for applying adhesive to fix the patches, means for applying gum to sealing flaps of the blanks, blank advancing means having connection with the patch affixing means and with the gum applying means including means for lapping the 10 blanks one over the other to expose the sealing flaps of the blanks to the gum applying means, means for simultaneously drying the gum on the sealing flaps and the adhesive whereby the patches are affixed to the blanks, and means for directly 15 delivering the blanks from the gum applying means to said drying means.
6. In a machine of the character described, the combination of means for moving blanks through a fixed path, means cooperating with the forwarding means for affixing a patch over a window opening in the blanks including means for applying adhesive to fix the patch, means for applying gum to sealing flaps of the blanks, blank advancing means having connection with the 20 patch affixing means and with the gum applying means, a drying tunnel for simultaneously drying the gum and effecting set of the adhesive whereby the patches are affixed to the blanks, and means for directly delivering the blanks from the gum applying means to said drying means.
7. In a machine of the character described, the combination of forwarding means for moving blanks through a fixed path, means located in the path of the blanks for spacing and aligning the 25 blanks on the forwarding means, means cooperating with the forwarding means and operating in timed relation with the spacing means for applying adhesive to edges of the window openings in the blanks, means cooperating with the forward- 30 ing means for applying patches over the window openings and into contact with the adhesive on the blanks, means for applying gum to a sealing flap of the blanks, means for directly delivering 35 the blanks from the patch affixing means to the gum applying means including means for overlapping the blanks to expose the sealing flaps of the blanks to the gum applying means, means for simultaneously drying the gum and effecting set of the adhesive, and means for directly delivering 40 the blanks from the gum applying means to the drying means.
8. In a machine of the character described, the combination of forwarding means for moving blanks through a fixed path, means located in the path of the blanks for spacing and aligning 10 the blanks on the forwarding means, means cooperating with the forwarding means and operating in timed relation with the spacing means for applying adhesive to edges of window openings in the blanks, means cooperating with the forward- 15 ing means for applying patches over the window openings and into contact with the adhesive on the blanks, means for applying gum to a sealing flap of the blanks, means for directly delivering 20 the blanks from the patch affixing means to the gum applying means including means for overlapping the blanks to expose the sealing flaps of the blanks to the gum applying means, means for simultaneously drying the gum and effecting set of the adhesive, and means for directly delivering 25 the blanks from the gum applying means to the drying means.
9. In a machine of the character described, the combination of means for affixing a patch over the window opening in a blank of foldable material including means for applying adhesive to fix the patch, means for folding the blank, drying means interposed between the patch fixing means and the blank folding means for effecting set of the adhesive whereby the patch is affixed to 30 the blank prior to folding of the blank, and blank advancing means supported in receiving relation with said patch affixing means and in direct delivery relation with said drying means whereby the blanks are delivered in continuous 35 movement to said drying means.
